ATTORNEY

UNITED STATES PATENT OFFICE.

JAMES G. WILSON, OF NEW YORK, N. Y.

DESIGN FOR A SHUTTER-SLAT.

SPECIFICATION forming part of Design No. 34,967, dated August 20, 1901.

Application filed July 18, 1901. Serial No. 68,853. Term of patent 14 years.

To all whom it may concern:

Be it known that I, JAMES GODFREY WILSON, a subject of Edward VII, King of Great Britain, residing at New York, in the county of New York and State of New York, have invented and produced a new and original Design for a Shutter-Slat; and I do hereby declare the following to be a full, clear, and exact description of the invention, such as will enable others skilled in the art to which it appertains to make and use the same.

Referring to the accompanying drawings, Figure 1 is a perspective of my design, and Fig. 2 a side elevation thereof.

Similar numbers of reference denote like parts in both figures of the drawings.

The leading features of my design are the two concavo-convex portions 1 2, which extend in reverse directions, one beginning at a point immediately beneath the free edge 3 of the upper part of the slat and continuing outwardly to a plane beyond the vertical plane of the hook-like formation 4 at the upper end of said slat, while the other begins at a point immediately above the free edge 5 of the hook-like formation 6 at the bottom of the

slat and likewise continues outwardly to a plane beyond the vertical plane of said hook-like formations.

The upper and lower edges of the slat are curled, so as to present the hook-like formations 4 6, whose free ends point toward each other. The concavo-convex portions 1 2 are between the horizontal planes of the free ends of these hooks, and these portions are joined together at the center of the slat. It is also material that the hook ends 4 6 should be turned outwardly toward the convex surfaces of the parts 1 2 at the ends of the slat, so that these hooks will be immediately beyond said convex surfaces at the points where they begin to swell outwardly.

I claim—

The design for a shutter-slat, substantially as shown and described. 45

In testimony whereof I affix my signature in presence of two witnesses.

JAS. G. WILSON.
